UNITED STATES PATENT OFFICE.

OSCAR W. MOORE, OF CHICAGO, ILLINOIS.

DESIGN FOR AN AUTOMOBILE RADIATOR CAP.

Application filed March 19, 1925. Serial No. 12,772. Term of patent 14 years.

To all whom it may concern:

Be it known that I, OSCAR W. MOORE, a citizen of the United States, residing at Chicago, in the county of Cook and State of Illinois, have invented a new, original, and ornamental Design for an Automobile Radiator Cap, of which the following is a specification, reference being had to the accompanying drawing, forming part thereof, in which:

Figure 1 is a plan view, and

Figure 2 is a front view showing my new design.

I claim:
The ornamental design for an automobile radiator cap as shown.

OSCAR W. MOORE.
